UNITED STATES PATENT OFFICE.

JOHANNES GABLER, OF MÜLHAUSEN, GERMANY.

SHUTTLE-BOX FOR BOBBIN-CHANGING LOOMS.

No. 926,480.

Specification of Letters Patent.

Patented June 29, 1909.

Application filed November 27, 1907. Serial No. 404,051.

To all whom it may concern:

Be it known that I, JOHANNES GABLER, engineer, a citizen of the German Empire, residing at Mülhausen, i. Els., Germany, have invented certain new and useful Improvements in Shuttle-Boxes for Bobbin-Changing Looms, of which the following is a specification.

This invention relates to improvements in shuttle boxes for bobbin-changing looms, and the objects of the invention are to provide for an effective checking of the shuttle from above, and at the same time avoiding the necessity of providing the shuttle box with a front wall, as also to obtain certain other advantages as hereinafter mentioned. I attain these objects by the construction as herein described and as illustrated in the accompanying drawing, in which—

20 Figure 1 is a front elevation of my improved shuttle box, Fig. 2 a plan view of the same, Fig. 3 a transverse section on the line A—B of Fig. 1, and Fig. 4 is another transverse section on the line C—D of Fig. 1.

25 In this improved construction the shuttle box is entirely open in front and has a rear wall *a* provided with an opening or passage *b* to permit the automatic bobbin change. At about a right angle to the said rear wall 30 is the bottom piece *c* serving, as customary, as a sliding track for the shuttle *d*. The front wall of the box being omitted altogether leaves the shuttle completely clear in front.

35 The track *c* is provided with one or more low stops *e* preventing lateral escape of the shuttle but without offering such obstruction as would tend to catch the weft thread. The lateral deviation of the shuttle from its regular course is prevented by providing, above said shuttle, a check-bar *f* swinging on a horizontal transverse pivot *h* and a spring *g* acting upon the back of the said bar and pressing it against the upper face of the 45 shuttle, the bottom face of the said bar and the said upper face of the shuttle being inclined, and thus resulting, owing to the stress of the spring *g*, in a wedge-action which presses the shuttle against the rear wall of 50 the shuttle-box, thus preventing lateral movement of said shuttle or deviation from its regular course.

55 The check bar *f* may also be utilized for the operation of the stop-motion rod *i* of the loom by the action of the shuttle in entering the box. For this purpose there is provided

at the rear wall of the box a support *k* in which is a pivot *l* on which moves a transversely disposed lever having arms *m*, *n*. The end of the front arm *m* rests upon the bar *f* and is raised by the latter whenever the shuttle enters the box. The rear arm *n* of the lever ends in an inclined smooth surface adapted to act by its rocking movement on a roller *p* adjustably secured on the end of an upright arm *o* mounted on the stop-motion rod *i*.

From the foregoing it will be apparent that the improved construction is such that the shuttle will be urged toward the rear 70 wall *a* of the shuttle-box by the wedging action resulting from the inclined contacting surfaces of the spring-pressed check-bar or tongue *f* and the upper face of the shuttle, and owing to the fact that the shuttle-box 75 has an open front there is little or no liability of accidentally catching the thread thereon. Also the checking of the shuttle is effected by the check bar or tongue *f* in an effectual and easy manner without jerks, 80 as a comparatively large surface is utilized in the checking action. Also, owing to the connection of the check bar or tongue *f* with the stop motion device, it will be apparent that the latter will be rendered inoperative 85 when the shuttle fails to enter the box; but should the shuttle fail to enter the box the stop motion device, controlled from the brake bar *f*, will be free to assume its operative 90 position to stop the loom.

I claim:

1. In a loom, the combination of a shuttle box open in front and having a rear wall provided with a passage adapted to permit automatic bobbin change, said shuttle box 95 having a bottom piece adapted to serve as a sliding track for the shuttle, a check bar swinging on a horizontal pivot above the face of the upper edge of the shuttle, and a spring acting upon the said bar, the bottom 100 face of the said bar and the upper face of the shuttle being inclined to provide for a wedging action to urge the shuttle toward said rear wall.

2. In a loom, the combination of a shuttle box open in front and having a rear wall provided with a passage permitting automatic bobbin change, said shuttle box having a bottom piece adapted to serve as a sliding track for the shuttle, a check bar swinging on a horizontal pivot above the face of the upper edge of the shuttle, a 105 110

spring acting upon the said bar, the bottom face of the said bar and the upper face of the shuttle being inclined to provide for a wedging action on the shuttle, a transversely disposed double-armed rocking lever supported on the rear wall of the shuttle box, the front of the said lever touching the upper surface of the check bar and the rear arm ending in an inclined smooth surface, and a stop-motion-controlling arm provided

with a roller engaged by said inclined smooth surface, substantially as described.

In testimony whereof I have signed my name to this specification in the presence of two subscribing witnesses.

JOHANNES GABLER.
